CLAIM

The ornamental design for a tray, as shown and described.

DESCRIPTION

FIG. 1 is a perspective view of a tray, as viewed from above, showing my new design;

FIG. 2 is a perspective view of the tray shown in FIG. 1, as viewed from below;

FIG. 3 is a front elevation view of the tray shown in FIG. 1;

FIG. 4 is a right side view of the tray shown in FIG. 1;

FIG. 5 is a rear elevation view of the tray shown in FIG. 1;

FIG. 6 is a left side rear elevation view of the tray shown in FIG. 1;

FIG. 7 is a top plan view of the tray shown in FIG. 1; and,

FIG. 8 is a bottom plan view of the tray shown in FIG. 1.

The broken lines shown in the drawings represent portions of the tray that form no part of the claimed design.
